UNITED STATES PATENT OFFICE.

ROBERT C. BARRIE, OF PHILADELPHIA, PENNSYLVANIA.

SURGICAL APPLIANCE.

No. 867,340.

Specification of Letters Patent.

Patented Oct. 1, 1907.

Application filed December 1, 1906. Serial No. 345,962.

To all whom it may concern:

Be it known that I, ROBERT C. BARRIE, a citizen of the United States, residing in the city and county of Philadelphia and State of Pennsylvania, have invented 5 a new and useful Improvement in Surgical Appliances, of which the following is a specification.

My invention relates to improvements in surgical appliances for the treatment of impotent procreative organs of the male sex, and the objects of my improvements are: first, to establish congestive turgidity within 10 the organ; second, to afford proper sustainment during functional exercise; third, to affect abdominal adaptation and length requirements of the device; fourth, to safeguard and facilitate coition in accordance with natural propensity. I attain these objects by the mechanism illustrated in the accompanying drawings in which—the figure represents a perspective of a complete device showing the arrangement of the several parts.

20 The basic portion of the appliance consists of a cone-shaped spiral spring (1) and the adjusting sleeve (3) and retaining screw (5). The paramount feature of this section requires the top coil of the spring to be diametrically less than the average organ when measured at its 25 base, whereby the restricted opening (2) serves to establish a primary stage of venal congestion; the inherent qualities of reciprocation permit the base coil (1) to conform to movement and position and the lower abdominal surface, and also proffers a cushioning resistance to undue thrusts, while the quality of strength affords means of sustainment to the rod and inclosed member.

30 The second part consists of a smoothly combined ring (7) and rod (6) preferably made of non-corrosive wire; 35 this second circle is equally important as coil (2) in part (1) as it coöperates therewith in producing complete turgidity wherefore the diameter thereof is smaller than the member when measured behind the corona glandis, the rod (6) serves to connect these rings

and to give horizontal support to the organ and incidentally guide the same during functional exercise. This rod should be made of full length to admit cutting to the requisite size as the case may require, after which the free end is inserted at (4) and retained by screw (5) and is thus adjustable in sleeve (3) when the device will 45 be complete.

In applying the mechanism the spring is passed over the member and against the lower abdominal surface when the ring (2) will compress the trunk at its base; next the glans-penis is drawn through ring (7) which 50 will likewise bind the organ directly behind the corona glandis where it will lie hidden by the gathered prepuce, the rod being obscure beneath the trunk and the spring veiled by the hirsute covering or wearing apparel, thus presenting a seemingly natural and unoffensive appearance to allay suspicion and fear of the opposite sex. If such application be made during movements of proclivity incentive desire and natural impulse will impel blood corpuscles into the vascular system of the organ and thus fully extend the trunk portion between the rings and likewise enlarge the glans-penis to a greater diameter than that of ring (2) which it will overlap and thus safeguard the orifice and walls of the vaginal canal from contact with said spring while under the guidance of the sustaining rod. 65

I am aware that prior to my invention the constructive parts thereof were commonly and variously combined for other purposes, I therefore do not claim such broadly, but

I claim:—

30 The combination in a surgical appliance of a conical spiral spring having a venal compressing coil (2) and attached adjusting sleeve (3) with a rod (6) and smoothly closed ring (7) alike coöperative with aforesaid coil all substantially as set forth.

ROBERT C. BARRIE.
